[57] CLAIM

The ornamental design for terminal wire holder, as shown and described.

DESCRIPTION

FIG. 1 is a perspective front view of a terminal wire holder embodying the present design in an unfastened position;

FIG. 2 is a perspective rear view thereof;

FIG. 3 is a front view thereof;

FIG. 4 is a rear view thereof;

FIG. 5 is a top plan view thereof;

FIG. 6 is a bottom view thereof;

FIG. 7 is a left side view thereof;

FIG. 8 is a right side view thereof;

FIG. 9 is a perspective front view thereof when a lever is locked; and,

FIG. 10 is an environmental perspective view thereof.

The broken line showing of wires and a fragmented wall is for illustrative purposes only and forms no part of the claimed design.
